UNITED STATES PATENT OFFICE.

FRANK WIBERLEY, OF NEW YORK, N. Y., ASSIGNOR TO BARTHELS MFG. COMPANY, OF BROOKLYN, NEW YORK.

SHIRT-WAIST SUPPORTER.

1,053,764.

Specification of Letters Patent. Patented Feb. 18, 1913.

Application filed May 24, 1911. Serial No. 629,110.

To all whom it may concern:

Be it known that I, FRANK WIBERLEY, a citizen of the United States, and a resident of the city of New York, Jamaica, borough 5 of Queens, in the county of Queens and State of New York, have invented a new and Improved Shirt-Waist Supporter, of which the following is a full, clear, and exact description.

10 The object of the invention is to provide a new and improved shirt waist supporter or a belt for conveniently holding the shirt waist in position at the waist of the wearer, and arranged for ready adjustment to suit 15 different sizes of waist measure, and for securely holding the supporter in adjusted position without the use of buckles and other fastening devices.

For the purpose mentioned, use is made 20 of a tubular covering, a band extending through the said covering and terminating in loops projecting beyond the ends of the covering, and a tying string doubled up to form an eye for engagement with one of the 25 said loops.

A practical embodiment of the invention is represented in the accompanying drawings forming a part of this specification, in which similar characters of reference indicate corresponding parts in all the views.

Figure 1 is a perspective view of the shirt waist supporter; Fig. 2 is an enlarged side elevation of part of the same, parts being broken out; and Fig. 3 is a sectional plan 35 view of one end of the belt.

The shirt waist supporter consists essentially of a belt A and a tying string B, of which the belt A is formed of a tubular braided covering C through which extends 40 a braided band D having its ends doubled up to form loops D' and D² projecting beyond the ends of the covering C, as plainly indicated in the drawings. The doubled-up portions of the band D are fastened together 45 by an eyelet, rivet or a like fastening device E, it being understood that the fastening means E are applied at the time the ends of the covering C are stripped far enough back for conveniently placing the fastening

means in position, and then the ends of the 50 covering C are pushed outward to cover up the fastening means E, after which rivets, eyelets or similar fastening devices F are employed for fastening the doubled-up portions of the band D to the terminals of the 55 covering C.

It is understood that by the arrangement described the loops are of a desired size and project the desired distance beyond the covering C.

The tying string B is preferably made of tubular braid, flattened and doubled up, with the doubled up portions fastened together by a rivet, eyelet or a similar fastening device G, located adjacent to the bend 60 of the tying string B so as to form an eye B' engaging the loop D', as plainly shown in Figs. 1 and 2. The terminals of the braid forming the tying string B are turned inward and the inwardly-turned ends are 65 fastened together by rivets, eyelets or similar fastening devices H to prevent raveling of the terminals of the tying string B. The doubled members B² and B³ of the tying string B are preferably of different lengths. 70

When using the shirt waist supporter, the belt A is passed around the shirt waist at the waist of the wearer, and then the ends of the two doubled up members B² and B³ of the tying string B are passed through 75 the loop D² so as to hold the shirt waist securely in position, and then the short member B² is dropped while the longer member B³ of the tying string B is passed through the other loop D' and tucked under, as indicated in Fig. 1, to hold the ends in place, thus requiring no buckles or similar fastening devices for the purpose. 85

The shirt waist supporter shown and described is very simple and durable in construction, and exceedingly strong and easily applied. 90

Having thus described my invention, I claim as new and desire to secure by Letters Patent:

A shirt waist supporter, comprising a belt formed of a band having its ends doubled up and secured to the band to form a loop or 95

eye at each end of the band, and a tubular covering on the band and extending over the doubled up portions to the loops or eyes thereof and having its ends secured to the said doubled up portions, and a tying string secured to one of the loops or eyes.

In testimony whereof I have signed my

name to this specification in the presence of two subscribing witnesses.

FRANK WIBERLEY.

Witnesses:

EMIL ROEHRIG,
A. W. UELLENDAHL.
